Mordicai Bell Greenwich N.Y. 6761X

Scallop Shell

The schedule referred to in the Letter Patent now making part of the same containing a description in the words of the said Mordicai Bell himself of his improvement in manufacturing Shells or Scallops from Sheet iron Copper tin &c.

Be it known that I Mordicai Bell of the town of Greenwich in the County of Washington and State of New York have invented and made improvement in manufacturing Shells or Scallops from Sheet iron Copper tin or any other metal and that the following is a full and exact description of the construction and operation of the said machine as invented or improved.

14, No. 1

I have a cast iron mould in shape of the Shell to be manufactured upon this I place my Sheet of iron Copper tin or any other metal. I then have a following mould nearly like the mould as to having space for the iron. I then lay any other metal upon the top of the following &c & then the casting a block of iron nearly green attached to the following and case with it with a notch in the top side which is fastened a bar of iron perpendicular about two inches to this I attach a lever which I cause at one end against anything that will hold it and thereby means of a force attached to the lever the following passes the iron, Copper tin or any other metal into the mould which when turned forces the blade of the scoop or shell. This is attached to a handle by means of a plate of iron secured underneath the scoop. Shell and a thin iron cage to cover the cage.

I make advantage of a pump audience or any other power necessary for moving the iron, Copper tin or any other metal into the mould.
